Primary Examiner — Zenia Bennett(74) *Attorney, Agent, or Firm* — Colorado Patents(57) **CLAIM**

The ornamental design for a low drag aquatic towing system, as shown and described.

DESCRIPTION

FIG. 1 is a perspective view of a low drag aquatic towing system for connecting a towing vehicle and a towed device showing my new design;

FIG. 2 is an enlarged perspective view of the low drag aquatic towing system shown in FIG. 1;

FIG. 3 is a left side view of the low drag aquatic towing system of FIG. 2 and wherein the right side view is the mirror image of the left side view;

FIG. 4 is a top plan view of the low drag aquatic towing system of FIG. 2 and wherein the bottom plan view is the mirror image of the top plan view; and,

FIG. 5 is a front view of the low drag aquatic towing system of FIG. 2 and wherein the rear view is the mirror image of the front view.

The broken lines are shown for illustrative purposes only and form no part of the claimed design.
